Primary Examiner — Philip S Hyder*Assistant Examiner* — Sydney Buffallow(74) *Attorney, Agent, or Firm* — Schneck & Schneck;
Thomas Schneck(57) **CLAIM**

I claim the ornamental design for an articulated support arm attachment for a table leg, as shown.

DESCRIPTIONFIG. 1 is an upper front perspective view of an articulated support arm attachment for a table leg of my design;
FIG. 2 is a lower front perspective view of the present invention in an extended state.

FIG. 3 is a bottom view thereof;

FIG. 4 is a top view thereof;

FIG. 5 is a quarter right side view thereof;

FIG. 6 is a quarter left side view thereof;

FIG. 7 is a full right side view thereof; and,

FIG. 8 is a full left side view thereof.
